UNITED STATES PATENT OFFICE.

WILLIAM P. SINGELTARY, OF ASHEVILLE, NORTH CAROLINA.

RAIL JOINT.

Application filed January 26, 1925. Serial No. 4,847.

To all whom it may concern:

Be it known that I, WILLIAM P. SINGELTARY, a citizen of the United States, residing at Asheville, in the county of Buncombe and State of North Carolina, have invented certain new and useful Improvements in Rail Joints, of which the following is a specification.

This invention relates to improvements in rail joints and has as one of its objects to provide a rail joint which will firmly and securely support and connect the meeting ends of rails with which it is assembled and will securely hold the rail ends against relative displacement and yet permit of expansion and contraction through temperature changes.

Another object of the invention is to provide a rail joint of such construction that the two companion members comprising the same will be firmly laterally braced and particularly at that portion opposite the point where the two rail ends will meet, so that the rail joint members will be capable of withstanding any severe strains to which the rails may be subjected and thus effectually prevent springing of the joint or any lateral displacement of the rail ends with respect to each other.

Another important object of the invention is to so construct the companion members of the joint that they will be effectually braced against sagging at their portions which extend between adjacent ties and which portions support the rail ends where they meet, thereby providing against any downward deflection of the rail ends and, as stated, any sagging of the members of the joint.

Another object of the invention is to provide a rail joint, the members of which will be so constructed as to firmly and securely bind against the base flanges of the rail ends so as to provide against any play between the rail ends and the joint.

Another important object of the invention is to so construct the members of the joint that they will effectually support the heads of the rails and thus further provide against any downward deflection of the rail ends.

In the accompanying drawings:

Figure 1 is a perspective view of the rail joint embodying the invention applied to the meeting ends of two rails.

Figure 2 is a vertical transverse sectional

view through the joint and rails taken substantially on the line 2—2 of Figure 1, looking in the direction indicated by the arrows.

Figure 3 is a side elevation of the ends of the rails to be supported and connected by the joint.

Figure 4 is a fragmentary sectional perspective view illustrating one of the members of the joint and the end of one of the rails.

In the accompanying drawings, the rails to be joined are indicated in general by the numeral 1, each rail comprising the usual head 2, web 3, and base flanges 4. The rails at their ends are provided with bolt openings and the openings in one rail, which openings are indicated by the numeral 5, are of circular contour and of a diameter to more or less snugly receive the shanks of the securing bolts which are indicated by the numeral 6. The corresponding openings in the other rail, which openings are indicated by the numeral 7, are of substantially elliptical form, as shown in Figure 3, and the openings in the two rails are formed of the different contours stated in order to permit of such slight longitudinal movement of the rail which is provided with the openings 7, with relation to the rail which is provided with the openings 5, as is necessary to compensate for expansion and contraction of the rails, it being understood that the second mentioned rail is therefore, permitted to have slight longitudinal movement in the rail joint of the present invention whereas the first mentioned rail which is provided with the openings 5, is so secured with relation to the rail joint as to prevent any such movement. Preferably, the rails are formed at their ends as illustrated in the several figures of the drawings, each rail having the end faces of its base flanges and web disposed in a vertical plane at right angles to the line of extent of the rail and each rail having its head 2 cut diagonally, as indicated by the numeral 8, so that the heads of the rails will meet on a diagonal line, thereby providing for smooth passage of the wheels of rolling stock over the rails, the right angular ends of the base flanges and webs, however, effectually preventing any shifting of the rail ends toward overlapping position as would be liable to occur if the ends of the rails were cut diagonally from top to bottom.

The members of the rail joint embodying the invention, indicated in general by the

numeral 9, are of counterpart construction and form and hence a description of one will suffice for both. Each of the members 9 comprises a base 10 which is flat upon its upper and under sides and of a width slightly less than one-half the width of the base flange 4 of the rail to be supported. A reinforcing web 11 is integral with the outer longitudinal side of the base 10 and occupies a vertical plane and extends both above and below the plane of the base, and the upper edge of the reinforcing web 11 is inclined downwardly from a point midway between its ends to finally merge at its ends with the upper side of a bearing flange 12 which extends inwardly from and is integral with the inner face of the said reinforcing web 11, the bearing flange 12 being inclined upwardly and inwardly from the said web and overlying the upper side of the base 10 in spaced relation thereto, the inclination of the flange 12 being such that the rail base flange will be snugly accommodated between the base 10 and the flange 12, the under side of the rail base flange resting firmly upon the upper side of the base 10 and the under side of the flange 12 bearing firmly against the upper side of the rail base flange. The lower edge of the web 11 is inclined upwardly from a point midway between its ends to finally merge with the under side of the base 10, and it will be evident that the portion of the flange which is of greatest height is located at a point substantially midway between the ends of the joint member 9 and, therefore, opposite the ends of the rails when the joint members are assembled with the rails, so as to effectually strengthen the joint members at this point. A short bracing and reinforcing web 13 is integral with and extends between the inner face of the upper portion of the web 11 and the outer face of a cheek piece 14 which is integral with and extends vertically from the upper side of the flange 12, the web 13 being likewise integral with the upper side of the said flange 12 and constituting a reinforcement between the web 11 and the cheek piece 14. A web 15 is formed integrally with the inner face of the lower portion of the web 11, in a plane with the web 13, and likewise is integral with the under side of the base 10 and serves to effectually brace the base 10 with relation to the reinforcing web 11. If desired, a reinforcing bead 16 may be formed upon the outer face of each reinforcing web 11 to extend vertically thereof opposite the webs 13 and 15.

It will be observed that the cheek member 14 is spaced outwardly from the inner edge of the flange 12 and will consequently be spaced from the web of the rail.

The numeral 17 indicates a rail head supporting shoulder which is formed integral

with and extends longitudinally of the upper edge of the cheek member 14 and this shoulder has its upper face 18 transversely inclined in a downward direction toward that side of the joint member which is presented to the rail, the shoulder projecting laterally beyond the face of the cheek member 14 which is presented toward the web of the rail, as indicated by the numeral 19, and the inclined face 18 of the said shoulder 17 seating firmly beneath the adjacent side of the head of the rail, as clearly shown in Figure 2 of the drawings. In order to add mass to the shoulder 17 and render the same more substantial, it is preferable that the shoulder be extended, as at 20, beyond the other face of the cheek member 14. The cheek members 14 of the joint members 9 are formed with bolt openings 21 to accommodate the bolts 6 and it will be understood at this point that when the bolts 6 are tightened, the edges of the flanges 12 and the edges of the projecting portions 19 of the shoulders 17 will be drawn firmly against the opposite sides of the rail webs and, likewise, the shoulders 17 will wedge beneath the opposite sides of the heads of the rails, the inclination of the under sides of the flanges 12 and the upper sides of the shoulders being opposite, as clearly shown in Figure 2.

In order that the joint members may be secured to the ties, the web 11 of each member is formed with an integral outstanding lug 22 having spike openings 23 therein, and preferably, the lugs are reinforced, as at 24, by portions integral with the upper sides thereof and with the outer faces of the respective webs 11.

From the foregoing description of the invention, it will be seen that there is provided an exceptionally efficient rail joint which is of such construction as to possess maximum strength at the points where it will be subjected to the greatest strain, thus preventing any downward deflection of the ends of the rails which it joins. It will also be observed that when the bolts 6 are tightened, the joint members wedge against the opposite sides of the rail ends and between the upper sides of the base flanges and the under sides of the heads, thereby adding great strength to the joint as a whole. It will also be observed that the bases 10 of the joint members extend beneath substantially the entire under surface of the base of the rails so as to support the same in a substantial manner.

In order that the nuts 6^a upon the bolts 6 may be conveniently tightened and removed respectively in applying and removing the members of the joint, the extensions 20 of the shoulders 17 are formed in their under sides with recesses indicated by the numeral 25, which recesses provide sufficient space to

accommodate the nut engaging head of the wrench usually employed in tightening such nuts.

It will be observed that the under sides 5 of the lugs or extensions 22 are in the same plane as the under sides of the base portions 10, so that they rest flat upon the upper sides of the respective ties and consequently the joined ends of the rails are afforded the same 10 firm bearing or support as is afforded by the ordinary tie plates which are disposed between other portions of the rails and the ties over which the rails extend.

Having thus described the invention, what 15 I claim is:

1. A rail joint consisting of a pair of counterpart members each comprising a base to support the base of a rail, a reinforcing web integral with the base and extending 20 along the outer edge thereof and projecting above and below the same, a bearing flange extending inwardly from the said web and above the said base, in spaced relation to the latter to engage over the base flange of 25 a rail disposed upon the base, a cheek member upstanding from the said bearing flange, a web extending upwardly from said bearing flange and having engagement with the reinforcement web and cheek member intermediate 30 the length thereof to brace the reinforcement web, and a rail head supporting shoulder extending along the upper edge of the cheek member.

2. A rail joint consisting of a pair of 35 counterpart members each comprising a base to support the base of a rail, a reinforcing web integral with the base and extending along the outer edge thereof, a bearing flange extending inwardly from the said web and above the said base, in spaced relation to the latter to engage over the base flange of a rail disposed upon the base, a cheek member upstanding from the said bearing flange, and a rail head supporting 40 shoulder extending along the upper edge of the cheek member, the said reinforcing web being increased in height from its ends to its intermediate portion.

3. A rail joint consisting of a pair of 45 counterpart members each comprising a base to support the base of a rail, a reinforcing web integral with the base and extending along the outer edge thereof, a bearing flange extending inwardly from 50 said web and above the said base, in spaced relation to the latter to engage over the base

flange of a rail disposed upon the base, a cheek member upstanding from the said bearing flange, a rail head supporting shoulder extending along the upper edge of the 60 cheek member, the said reinforcing web being increased in height from its ends to its intermediate portion, and a reinforcing web integral with and extending between the 65 said cheek member and the said intermediate portion of the first mentioned reinforcing web.

4. A rail joint consisting of a pair of counterpart members each comprising a base to support the base of a rail, a reinforcing web integral with the base and extending along the outer edge thereof, a bearing flange extending inwardly from the said web and above the said base, in spaced relation to the latter to engage over the base 70 flange of the rail disposed upon the base, a cheek member upstanding from the said bearing flange, a rail head supporting shoulder extending along the upper edge of the 75 cheek member, the reinforcing web extending above and below the base, bracing webs extending inwardly from the extended upper and lower portions of said reinforcing web and joined to the bearing flange and base, the upper bracing web being also joined 80 to said cheek member and disposed directly above the lower bracing web, and a reinforcing rib formed vertically upon the outer face of said reinforcing web opposite said bracing webs.

5. A rail joint consisting of a pair of counterpart members each comprising a base to support the base of the rail, a reinforcing web integral with and extending along the outer longitudinal edge of the base, a bearing flange integral with and extending along the inner side of the said web and likewise integral with the base, a cheek member extending upwardly from the said bearing flange and longitudinally of the same, a rail 95 head supporting shoulder extending along the upper edge of the said cheek member, a reinforcing web integral with and extending between the intermediate portion of the first mentioned web and the outer face of 100 the cheek member, and a reinforcing web integral with and extending between the under side of the base and the inner side of the intermediate portion of the first mentioned reinforcing web.

In testimony whereof I affix my signature.
WILLIAM P. SINGELTARY. [L. S.]
